US0D1071160S

(12) **United States Design Patent** (10) **Patent No.:** **US D1,071,160 S**
(45) **Date of Patent:** **** Apr. 15, 2025**

(54) **HANDHELD DRUG DELIVERY DEVICE**

(71) Applicant: **AMGEN INC.**, Thousand Oaks, CA (US)

(72) Inventors: **Matias Melander**, Copenhagen (DK); **Bjarke Lykke Ludvig Svendsen**, Slagelse (DK); **Christian Plambech**, Soeborg (DK); **Michael Sorensen**, Jyllinge (DK); **Dylan Bourelle**, Woodland Hills, CA (US)

(73) Assignee: **AMGEN INC.**, Thousand Oaks, CA (US)

(**) Term: **15 Years**

(21) Appl. No.: **29/887,155**

(22) Filed: **Mar. 17, 2023**

Related U.S. Application Data

(62) Division of application No. 29/776,495, filed on Mar. 30, 2021, now Pat. No. Des. 985,119.

CLAIM

The ornamental design for a handheld drug delivery device as shown and described.

DESCRIPTION

FIG. 1 is a perspective view showing a new design for a handheld drug delivery device;

FIG. 2 is a front view of the handheld drug delivery device of FIG. 1;

FIG. 3 is a rear view of the handheld drug delivery device of FIG. 1;

FIG. 4 is a right-side view of the handheld drug delivery device of FIG. 1;

FIG. 5 is a left-side view of the handheld drug delivery device of FIG. 1;

FIG. 6 is a top view of the handheld drug delivery device of FIG. 1;

FIG. 7 is a bottom view of the handheld drug delivery device of FIG. 1; and,

FIG. 8 is a perspective view of the handheld drug delivery device of FIG. 1.

The broken lines in the drawings illustrate portions of the handheld drug delivery device and form no part of the claimed design.

UNITED STATES PATENT AND TRADEMARK OFFICE
CERTIFICATE OF CORRECTION

PATENT NO. : D1,071,160 S
APPLICATION NO. : 29/887155
DATED : April 15, 2025
INVENTOR(S) : Matias Melander et al.

Page 1 of 1

It is certified that error appears in the above-identified patent and that said Letters Patent is hereby corrected as shown below:

On the Title Page

In Column 2, under "DESCRIPTION", Line 12, "FIG. 1," should be -- FIG. 1; --.

In Column 2, under "DESCRIPTION", Line 16, "FIG. 1." should be -- FIG. 1 with its cap removed. --.

Signed and Sealed this
Eighteenth Day of November, 2025

John A. Squires
Director of the United States Patent and Trademark Office
